EMBROIDERED FABRIC

Filed July 1, 1946

ANTON WALTER

INVENTOR,

BY Louis Schumacher

ATTORNEY.

UNITED STATES PATENT OFFICE

145,682

DESIGN FOR AN EMBROIDERED FABRIC

Anton Walter, New York, N. Y.

Application July 1, 1946, Serial No. 131,229

Term of patent 3½ years

(Cl. D92—1)

To all whom it may concern:

Be it known that I, Anton Walter, a citizen of the United States of America, residing in New York city, county of New York, and State of New York, have invented a new, original, and ornamental Design for an Embroidered Fabric, of which the following is a specification, reference being had to the accompanying drawing, forming part thereof, wherein,

The figure is a plan view of a piece of embroidered fabric showing my new design.

I claim:

The ornamental design for an embroidered fabric, substantially as shown.

ANTON WALTER.
